CLAIM

The ornamental design for a side rail for a bed, as shown and described.

DESCRIPTION

FIG. 1 is a perspective view of a siderail showing its profile as seen from the laterally outboard side of the siderail.

FIG. 2 is a perspective view of the siderail showing its profile as seen from the laterally inboard side of the siderail.

FIG. 3 is an outboard side elevation view of the side rail for a bed; and,

FIG. 4 is an inboard side elevation view of the side rail for a bed.

The broken lines are for environmental purposes only and form no part of the claimed design.

1 Claim, 4 Drawing Sheets
